United States Patent Office

Des. 219,422
Patented Dec. 15, 1970

219,422

KNOB

Raymond U. H. Tegner, Rockford, Ill., assignor to
Amerock Corporation, Rockford, Ill., a corporation of
Connecticut

Filed Oct. 16, 1969, Ser. No. 19,592

Term of patent 14 years

Int. Cl. D8—03

U.S. Cl. D8—144

FIG. 1 is a front view of a knob incorporating my new design.

FIG. 2 is a side view of the knob.

FIG. 3 is a sectional view taken along the line 3—3 in FIG. 1.

FIG. 4 is a sectional view taken along the line 4—4 in FIG. 1.

FIG. 5 is an enlarged fragmentary sectional view taken along the line 5—5 in FIG. 1.

I claim:

The ornamental design for a knob, as shown.
